COLLAPSIBLE EGG CASE

Charles McKim, Dillsboro, Ind.

Application November 16, 1935, Serial No. 50,214

2 Claims. (Cl. 217—48)

This invention relates to new and useful improvements in collapsible egg cases.

One object of my invention is to provide an egg case that may be readily collapsed to render it more compact, and thus facilitate shipping and storage.

A further object of my invention is to provide a collapsible egg case that will be a great convenience to farmers and producers who haul their eggs to market in automobiles or trucks, by reason of the fact that access may be easily and readily gained to the contents of the case without the expenditure of the usual time and labor required to remove and nail the top back in place, and for the further reason that after sale or delivery of the product, the case may be collapsed to render same more compact and thus provide additional space for merchandise on the return trip.

With the foregoing and other objects in view that will appear as the nature of my invention is better understood, the same consists in the novel features of construction, combination and arrangement of parts illustrated in the accompanying drawings and more particularly pointed out in the appended claims.

In the accompanying drawings, which are for illustrative purposes only and are therefore not drawn to scale:

Figure 1 is a top plan view of an egg case, embodying my improvements.

Figure 2 is a bottom plan view.

Figure 3 is a vertical longitudinal section, taken on line 3—3 of Figure 1.

Figure 4 is a vertical transverse section, taken on line 4—4 of Figure 1.

Figure 5 is an enlarged diagonal section, taken on line 5—5 of Figure 1 and the remaining views are details of various features of my invention.

Referring to the drawings for a more particular description of my invention, and in which drawings like parts are designated by like reference characters throughout the several views, the numeral 1 designates the top, 2 the bottom, 3 and 3' the ends and 4 and 4' the sides of my improved collapsible egg case. The aforesaid parts are made in individual units and may be removably fastened together in the proper relationship, in the manner hereinafter described, to provide a strong, rigid and durable case for the shipment of eggs or other products, or may be collapsed to render the case very compact. This facilitates transportation or storage and provides additional space on the return trip for mer-

chandise, after the product has been sold or delivered.

In carrying out my invention, the side and end members are removably connected together at the four corners, and at the top and bottom of the case, by the upper and lower diagonal fastening members 5 and 6, respectively, each consisting of a pair of corresponding links 7 and 8 connected together at their inner ends by the eyes 9 and formed at their outer ends with the vertical right-angularly bent portions 10, which extend through corresponding vertical openings 11 and 12 in the upper and lower re-inforcing bars 13 and 14, respectively.

The interior of the case is divided into two corresponding compartments 15 and 16, by the central transverse partition 17, and this partition is held in removable position by the hooks 18 engaging the eyes 19.

When the top and bottom of the case are in place, the corners thereof fit under the upper and lower diagonal fastening members 5 and 6, and the top may be additionally secured in place by the hooks 20. The hooks 20 comprise the vertical arms 21, which are pivoted in corresponding openings 22 in the upper re-inforcing bars 13, and the off-set horizontal body portions 23 adapted to fit over and embrace the cross re-inforcing strips or slats 24 fastened to the upper face of the top. The outer ends of the body portions 23 are formed with hooks 25 adapted to engage corresponding eyes 26, secured to the upper edges of the re-inforcing bars 13. Hooks and eyes may also be associated with the bottom, if desired.

My improved collapsible case may be constructed with less lumber, and will have a much longer life than the ordinary case, since the constant nailing and withdrawal of nails impairs and shortens the life of the latter.

From the foregoing description taken in connection with the drawings, it is thought that the construction, operation and advantages of my invention will be readily understood, without requiring a more extended explanation.

Having described my invention, what I claim as new and desire to secure by Letters Patent, is:

1. A collapsible egg case, comprising individual top, bottom, side and end members, and diagonal fastening members for connecting the side and end members together at the corners and at both the top and bottom of the case, each of said fastening members comprising a pair of corresponding links formed at their inner ends

with hinged interlocking eyes and terminating at their outer ends in vertical portions engaging corresponding openings in the side and end members, and a transverse partition dividing the case into two corresponding compartments.

2. A collapsible egg case, comprising individual top, side and end members, diagonal fastening members for connecting the side and end members together at the corners and at both the top and bottom of the case, each of said fastening members comprising a pair of corresponding links formed at their inner ends with hinged

interlocking eyes and terminating at their outer ends in vertical portions engaging corresponding openings in the side and end members, a transverse partition dividing the case into two corresponding compartments, cross re-inforcing strips on the upper face of the top and hooks and eyes for removably securing the top in place, said hooks having offset horizontal body portions adapted to fit over and embrace the cross re-inforcing strips. 5
